UNITED STATES PATENT OFFICE.

ALFRED T. TREGURTHA, OF EVERETT, ASSIGNOR OF ONE-HALF TO HENRY A. CLARK, OF BOSTON, MASSACHUSETTS.

CUT-OUT.

SPECIFICATION forming part of Letters Patent No. 449,767, dated April 7, 1891.

Application filed February 25, 1889. Serial No. 301,102. (No model.)

To all whom it may concern:

Be it known that I, ALFRED T. TREGURTHA, of Everett, in the county of Middlesex and State of Massachusetts, have invented certain 5 new and useful Improvements in Electrical Cut-Outs, of which the following is a full, clear, and exact description.

This invention consists of the construction and arrangement of parts in an electric circuit to a light or other electric device connected to a main electric circuit, so that the electric circuit to the light or other electric device can be connected to or cut out from the main electric circuit for the repairing or 10 replacing of the parts making this electric circuit or for other purposes without disturbing or interfering with the light or other electric device in connection therewith as to its support or location, all substantially as 15 hereinafter fully described, reference being had to the accompanying sheets of drawings, in which—

Figure 1 represents a perspective view of the present device in connection with an incandescent lamp and as connected to wires 20 of a main electric circuit, the parts being supported from the ceiling of a room. Fig. 2 is a perspective view of the parts separated. Fig. 3 is a horizontal section on line 3 3, Fig. 1. Fig. 4 is a detail cross-section on line 4 4, Fig. 3. Fig. 5 is a detail cross-section on line 25 5 5, Fig. 1. Fig. 6 is a view similar to Fig. 1, to be hereinafter more particularly referred to. Fig. 7 is a perspective view of Fig. 6, similar 30 to Fig. 2. Fig. 8 is a horizontal section on line 35 8 8, Fig. 6.

In the drawings, A represents a circular base of wood or other suitable material adapted to be secured to the ceiling or any 40 suitable support in any desirable manner, having a rim or flange B, with a shoulder or recess C, forming a central depression or chamber D.

E F are two metal blocks inserted and secured in the flange B by screws d, flush with the same and diametrically opposite to each other, and each having an open slot or groove G in its outer end, in which is placed an electric wire H in the main circuit, which wire

rests in a groove a in the part b of the block, 50 a screw d screwing through its other part e, arranged to bear against and hold the electric wire in its block-groove a, by which each main electric wire is secured to its respective contact-block E or F, and the wires to the 55 base, the base being cut away, as shown at f, each side of the contact-block to allow of the insertion of the electric wire in place. Each block on its outer side has an arm h projecting toward the center of the base a short distance over the chamber D, and the inner or under side m of such arm is inclined or beveled outwardly, as shown.

J K are metal strips or plates secured to the bottom of the chamber each by screws n 65 r, and each having a raised right-angled projecting arm L, the two projecting in opposite directions, their under or inner faces t being inclined outwardly.

M is a circular block of wood or other suitable material of a diameter to fit within the recess C of the base and having secured to its inner face four metal plates or strips N P Q R each by screws u, and each having its outer or free end v bent slightly upward and 70 inclined, the plates being secured in such position on the face of the cover in relation to each other and the contact-blocks E F and arms L L of the plates J K on the base that when the cover is placed in the recess C of 75 the base, its face inward, the plate N between the arm L of plate J and contact-block E and the plate R between arm L of plate K and contact-block F, and then turned to the right, the ends v of the cover-plates P N will 80 pass, respectively, under the contact-block E and arm L of plate J and the cover-plates Q R will pass, respectively, under the contact-block F and arm L of plate K, the spring of 85 the metal plates holding the cover in place on the base, and which also maintains the electric circuit with the main wires.

Attached to the screw r of the plate J is an insulated electric wire S, and to the screw r of the other plate K is another insulated electric wire T, which wires are twisted together and passed through a central opening or passage w in the cover, and their other ends are

connected to the incandescent lamp U in the usual and well-known manner, these wires S T serving as electric conductors from the plates on the base to the lamp, and also as a means of suspending or supporting the lamp from the base and entirely independent and free of the cover.

The strips or plates on the cover are connected together by a fusible wire y, as shown.

When all parts are together and the electric current is turned on the main wires, it passes from the electric wire H' to contact-block E, to the plate N, through its fusible wire y, to plate P, to angular arm L of plate J, to insulated wire S, to the lamp, and returns through the insulated wire T, angular arm L of plate K, to plate Q, through its fusible wire y, to plate R, contact-block F, and to the other electric wire H, or vice versa, as the case may be, according as the electric current flows one way or the other. To remove the cover, turn it to the left or in the reverse direction from that by which it was secured in place, which disengages the several plates on the cover from the contact-blocks and arms on the base, when it can be moved from the base along the lamp-wires, as shown in dotted lines in Fig. 1, the opening in the cover being large enough to allow of its free movement thereon. The parts can then be repaired or changed, as desired, and the cover be replaced in position, making the electric circuit complete with the lamp and main circuit and all without disturbing or interfering with the lamp so far as its support is concerned, thus obviating any and all liability of injuring or breaking the lamp and its connecting-wires—an advantage which is very desirable.

In Figs. 6, 7, and 8 is shown a way of supporting the lamp from the base, without the lamp-wires passing through the cover, the lamp-wires in these views being entirely outside of it, so that when the cover is detached from the base it can be removed entirely from the same and independent thereof and the lamp or its wires. In these views metal blocks V W are secured in the flange of the base between the electric contact-blocks E F, equidistant from the same, and are secured each by a screw a', screwing through the back of the base into a projecting portion b' of the block, as shown. Each of these blocks has a projecting portion d' over the chamber, their under faces e' being inclined in a similar manner to the projecting portions of the contact-blocks E F.

The four plates N P Q R on the cover are secured radially by screws u equidistant from each other, and when the cover is placed on the base and turned to the right or left the ends v of these plates pass under the projecting end of the blocks V W and contact-blocks E F on the base, which secures the cover to the base and makes electric contact with the parts, and being equidistant from each other, as described, and having their faces inclined

alike, the cover can be put on at any point and then turned and secured.

One insulated wire T of the lamp is connected by the screw A' to one block W, and the other wire by the screw B' to the other block V, and both then pass from the base outside of the cover a sufficient distance to be free of the same, and are then twisted together and at such place pass through a passage in a small ball C', which prevents their untwisting or separating.

The base and cover can be made of any suitable material that is a good non-conductor of electricity. Although being made of wood, they can be made cheaply and quickly. If made of an electric conducting material, the various connecting parts should be properly insulated.

By this device, when it is desired to cut out the electric circuit to any particular lamp, or when any of the parts require replacing or to be repaired, it can be done by removing the cover, and that without interfering or disturbing the lamp as to its support or location—an advantage which is very desirable in electric circuits carrying one or more incandescent lamps and an improvement over electric cut-outs now in use, where the lamp is connected to the cover in lieu of the base, the removing of the cover of which necessitates the moving of the lamp, and thus increases the liability of injuring and breaking of the lamp, as is obvious.

I do not claim in this application the electric block as a means of making electric contact between the electric wires and the electric lamp and of securing the cover to the base, as that is the subject of an application of mine, filed April 17, 1890, Serial No. 348,338.

Having thus described my invention, what I claim is—

1. The combination, with a base having electric contacts thereon for connection with the main wires of the electric circuit and a lamp having its electric wires each connected to an independent electric contact on said base, by which wires the lamp is suspended and supported, of a cap or cover having electric contacts on its inner side, each two connected by a separate fusible electric wire, and said electric contacts being arranged to engage with and to be connected to the electric contacts on said base to make electric connection therewith and to secure and hold said cap or cover in position on the base.

2. The combination, with a base having electric contacts thereon for connection with the main wire of the electric circuit and a lamp having its electric wires each connected to an independent electric contact on said base, by which wires the lamp is suspended and supported, of a cap or cover having electric contacts on its inner side, each two connected by a separate fusible electric wire, and said electric contacts being arranged to engage with and to be connected to the elec-

tric contacts on said base to make electric connection therewith and to secure and hold said cap or cover in position on the base, and said cap or cover having an opening or passage through it, through which the electric-lamp wires freely extend, substantially as and for the purpose specified.

In testimony whereof I have hereunto set my hand in the presence of two subscribing witnesses.

ALFRED T. TREGURTHA.
